US0D1065688S

(12) **United States Design Patent** (10) **Patent No.:** **US D1,065,688 S**
(45) **Date of Patent:** **** Mar. 4, 2025**

(54) **NAIL POLISHER**

(71) Applicant: **SHENZHEN GUOYUCHEN TECHNOLOGY CO., LTD.**, Shenzhen (CN)

(72) Inventor: **Qing Lv**, Shenzhen (CN)

(73) Assignee: **SHENZHEN GUOYUCHEN TECHNOLOGY CO., LTD.**, Shenzhen (CN)

(**) Term: **15 Years**

(21) Appl. No.: **29/848,505**

(22) Filed: **Aug. 3, 2022**

(30) **Foreign Application Priority Data**

Jun. 8, 2022 (CN) 202230346466.2

(51) **LOC (15) Cl.** **28-03**

(52) **U.S. Cl.**

USPC **D28/59**; D28/58

(58) **Field of Classification Search**

USPC D28/57, 58, 59; 132/73, 73.5, 76.4

CPC A45D 29/00; A45D 29/05; A45D 29/11;

A45D 29/14; A45D 29/17; A45D 29/18

(57) **CLAIM**

The ornamental design for a nail polisher, as shown and described.

DESCRIPTION

FIG. 1 is a front elevational view of a nail polisher showing my new design;

FIG. 2 is a rear elevational view thereof;

FIG. 3 is a left side elevational view thereof;

FIG. 4 is a right side elevational view thereof;

FIG. 5 is an enlarged top plan view thereof;

FIG. 6 is an enlarged bottom plan view thereof;

FIG. 7 is a first perspective view thereof shown; and,

FIG. 8 is a second perspective view thereof shown.

The broken lines depict portions of the nail polisher that are for illustrating the boundary of the design only and do not form part of the claimed design.

1 Claim, 8 Drawing Sheets
